CALCULATING MACHINE

Carl M. F. Friden, Oakland, Calif., assignor to
 Friden Calculating Machine Co., Inc., a corpora-
 tion of California

Application April 20, 1936, Serial No. 75,307

2 Claims. (Cl. 235—75)

The present invention relates to calculating machines and more particularly to an improved calculating machine of the Thomas type, such as shown in Felt et al., Serial No. 1,612,969, dated January 4, 1927, in which special transfer and actuating mechanism is provided to enable reduced width of the machine. This application is a continuation in part of my co-pending application, Serial No. 724,482, filed May 8, 1934.

In previous machines of this type as illustrated by the Felt et al. structure, it has been customary to place the actuating cylinders on an equal number of longitudinally extending actuating shafts which are spaced apart transversely of the machine to provide clearance between adjacent cylinders. As a result, machines of this type have been very wide and consequently, cumbersome to handle. This large size has also caused considerable sales resistance.

I have found that the width of machines of this type can be reduced to a convenient, desirable size by placing a plurality of the actuating cylinders on the same actuating shaft, and by associating therewith a transfer mechanism in which the transfer actuators are mounted similarly. The actuating and transfer mechanisms are mounted preferably in angularly offset relation to enable a complete ordinal transfer in succession from the lowest through the highest order, and have the associated selecting mechanism grouped with respect thereto to accommodate the special arrangement thereof.

It is an object of the invention, therefore, to provide a calculating machine of the character referred to, in which the actuating and transfer mechanisms are constructed to enable reduced width of the machine.

Another object of the invention is to provide a calculating machine of the character referred to, which is compact and easy to handle.

A further object of the invention is to provide actuating mechanism for a calculating machine in which the actuating mechanism of adjacent orders are over-lapped to enable reduced width of the machine.

Another object of the invention is to provide an improved transfer mechanism for calculating machines of the character referred to, which contributes to reduced machine width, and enables a full ordinal transfer.

Other objects will appear as the description progresses with reference to the accompanying drawings in which the various parts are shown full size.

In the drawings:

Figure 1 is a partial vertical longitudinal section taken through the axis of an actuating shaft as indicated by the line 1—1 in Figure 3 with certain parts shown in elevation.

5 Figure 2 is a bottom view of an end of the shiftable accumulator carriage, certain of the parts being shown in section to illustrate details of construction.

Figure 3 is a fragmentary plan view of the actuating and transfer mechanisms, with the numeral keys and accumulator carriage omitted for better illustration of the construction.

10 Portions of the selecting and actuating mechanism are omitted in certain orders to illustrate 15 various details of construction.

Figure 4 is a transverse vertical section of the actuating and transfer mechanisms taken in a plane indicated by the line 4—4 in Figure 1.

Figure 5 is a section similar to Figure 4 20 through two orders of the machine, and shows one of the transfer actuators in active position.

Figure 6 is a transverse vertical section illustrating another portion of the transfer and actuating mechanisms and is taken in a plane indicated by the line 6—6 in Figure 1.

Figure 7 is a vertical transverse section illustrating the actuating and transfer mechanisms and is taken in a plane indicated by the line 7—7 in Figure 1.

30 Figure 8 is a schematic view similar to Figure 7 and illustrates the angularly staggered relation of the various orders of the actuating mechanism and the transfer actuators.

As stated above, the present invention is concerned primarily with calculating machines of the Thomas type which generally include a body in which the selecting, actuating and transfer mechanisms are mounted and a shiftable register carriage, which also supports a part of the transfer mechanism. In the preferred embodiment of my invention disclosed herein, the body of the calculating machine includes base 10 (Fig. 1) having casing 11 and a plurality of similar side frame members 12 (Figs. 1 and 3) 35 mounted thereon, only one of frame members 12 is seen in the drawings. Between respective side members 12, a plurality of transverse frame members 13, 14, 15, 16 (Fig. 1) are provided to support various parts of the calculating mechanism referred to hereinafter.

Shiftable register carriage 21 (Fig. 1) is mounted for endwise shifting movement by suitable rollers 22 on transverse frame members 13 and 16 and has frame 23 in which a numeral 55 wheel shaft 24 for each order of the register is

journaled. At its upper end each shaft 24 carries numeral wheel 26 having the digits from zero to 9 inscribed thereon in the conventional manner, and at its lower end carries ten tooth numeral wheel gear 27. Intermediate its ends, each shaft 24 carries ten tooth ratchet gear 28 with which spring urged ball 29 cooperates to maintain numeral wheel 26 in adjusted position. Shaft 24 also carries resetting gear 30 for cooperation with suitable resetting means not shown.

Numerical wheels 26 are rotatable in either direction to register positive and negative values and for this purpose gear 27 has associated therewith a pair of opposed bevel gears 31, 32 formed at the ends of spool 33. The shifted positions of gears 31, 32 are controlled by transversely extending strap 34 positioned between each pair of gears 31, 32 of the various orders of the machine. Strap 34 may be mounted in a convenient manner for movement forwardly and rearwardly of its central neutral position shown in Figs. 1 and 3 to engage gears 31 or 32 with numeral wheel gears 27. Thus, if gears 31 are engaged with gears 27, positive actuation of the associated numerical wheels 26 will occur, and, conversely, if gears 32 are engaged with gears 27, negative actuation of numerical wheels 26 is determined.

From the above description, it is seen that any increment of movement of a spool 33 will be transmitted to the associated numerical wheel 26 if either of gears 31 or 32 is placed in active position. Means are provided in the various orders of the machine to determine the number of increments of such movement. For this purpose a bank of numeral keys 41 is provided for each order of the machine, only a part of one of such banks is shown in Figure 1. The numeral keys 41 of each order of the machine cooperate with a pair of differential value selecting slides 42, 43 (Figs. 1, 3, and 7) which are mounted for endwise shifting movement and are provided with cam surfaces of varying inclination so that slides 42, 43 are set differentially in accordance with the value of the depressed numeral key. Slide 42 is associated with numeral keys 41 determining values from six to nine, and slide 43 is associated with numeral keys 41 determining values from one to five. At their rearward ends, slides 42, 43 (Fig. 1) carry respective ten tooth gears 46, 47 which cooperate respectively with the two sets of stepped teeth 48, 49 on an actuating cylinder 51 of the digitation actuating mechanism. Gears 46, 47 are mounted for sliding movement on square shaft 52 having its front end journaled in frame member 15 and extending rearwardly through frame member 14 and spool 33, and having its rear end journaled in frame member 13. Teeth 48 cooperate with gear 46 in their relatively adjusted positions to determine movement of shaft 52 for from six to nine increments, while teeth 49 and gear 47 cooperate to determine movement of shaft 52 for from one to five increments. The provision of two sets of teeth 48, 49 on each cylinder 51 and two value selecting slides 42, 43 enables short endwise movement of slides 42, 43 and provides for a light, substantially uniform key action.

In order to provide for reduced width of the machine, a plurality of actuating cylinders 51 (Figs. 1 and 3) for adjacent orders of the machine are mounted in longitudinal alignment on each actuating shaft 56. In the embodiment shown, a pair of cylinders 51, 51A are mounted on each shaft 56 for a pair of adjacent orders, the respective

selecting shafts 52 of such adjacent orders being spaced to either side and above the associated actuating shaft 56 as clearly seen in Figures 3 and 7. Referring to Figure 1, it will be noted that teeth 48A, 49A of the lower order cylinder 51A are offset angularly with respect to teeth 48, 49 of higher order cylinder 51. Each actuating shaft 56 is journaled in frame members 14 and 15 and at its front end has a bevel gear connection 57 (Figs. 1 and 3) with transverse shaft 58. Shaft 58 has its ends journaled in respective side members 12 and is driven cyclically from a suitable source of power such as an electric motor, or a hand crank. In the embodiment shown, one cycle of operation is effected by one rotation of shaft 58. Thus, for each rotation of shaft 58, shafts 56 and cylinders 51 also have a single rotation to cause registration of the number selected by the depressed numeral keys 41 on the associated numerical wheels 26. Certain of shafts 56 (Figs. 1 and 3) are extended rearwardly to provide drive connections for machine functions which are not necessary to an understanding of the instant invention.

From the above description it will be noted that for each adjacent pair of the transversely spaced orders of the selecting mechanism there is provided a single longitudinal actuating shaft having the pair of actuating cylinders for the respective orders of the selecting mechanism mounted thereon in longitudinal alignment and for rotation about the same axis. In order to distribute the driving load more evenly throughout the digitation part of a cycle of operation, the stepped teeth 48, 49 of the respective actuating cylinders 51 are mounted in angularly offset relation as seen in Figure 7, and as indicated diagrammatically in Figure 8. The arrangement is such that the teeth in the units and tens orders become active first and the others in succession thereafter.

Means are provided for preventing over-throw of the numeral wheels at the end of an actuation thereof and for this purpose the two sets of stepped teeth 48, 49 (Fig. 1) of each cylinder 51 are located with their last active teeth in alignment and there is associated with each shaft 52, a Geneva wheel having a locking disk cooperating therewith and mounted on the associated actuating shaft 56. As seen in Figs. 1 and 6, each shaft 52 has Geneva wheel 61 mounted thereon for rotation therewith, hub 62 of such wheel 61 being journaled in frame member 14 to support shaft 52. Associated with each Geneva wheel 61 is a locking disk 63, having a recessed portion 64 extending around its periphery for a distance corresponding to the distance occupied by teeth 48 on the associated cylinder 51. Each Geneva wheel 61 has ten concave faces 66 for cooperation with the associated disk 63 so that for each increment of movement imparted to shaft 52 and Geneva wheel 61 by one of teeth 48 or 49, one of faces 66 is positioned for cooperation with associated disk 63. The trailing edge 65 of recessed portion 64 moves into engagement with Geneva wheel 61 immediately after the last active tooth of teeth 48, 49 has actuated one of gears 46 or 47 so that the associated shaft 52 and, consequently, the associated numerical wheel 26, are positively locked against further rotation. To center shaft 52 and Geneva wheel 61 in position after movement thereof, shaft 52 carries ten tooth ratchet gear 67 (Figs. 1 and 4) adjacent frame member 13 which has spring-pressed ball 68 mounted therein for cooperation with gear 67.

Each pair of locking disks 63 and 63A for adjacent orders of the machine are mounted on an actuating shaft 56 in axially offset relation, in the same manner and for the same purpose as the similar mounting of the associated actuating cylinders 51. It will be noted also that recessed portions 64, 64A of the respective locking disks 63, 63A are angularly offset similarly to sets of teeth 48, 49 and 48A, 49A of the associated actuating cylinders 51, 51A.

Transfer mechanism of special construction is provided for cooperation with the actuating cylinders described above in enabling reduced width of the machine. Generally such transfer mechanism comprises tripping means associated with each numeral wheel, except that of highest order, for enabling a drive connection from a transfer actuator to the numeral wheel of next higher order, so that such next higher order numeral wheel receives one increment of movement when the numeral wheel of lower order passes from 9 to 0 or 0 to 9. The sign character of the transferred increment is determined in the same manner as the sign character of the digitation.

To effect the tripping of a transfer, each 25 numeral wheel shaft 24 (Figs. 1 and 2) is provided with single tooth gear 71 immediately below carriage frame 23 for cooperation with tripping lever 72, pivoted at 73 in frame 23 and yieldably held in frame 23 by spring-pressed ball 14 engaging a transverse notch in pivot 73. Lever 72 has extension 75 (Fig. 2) positioned in the path of single tooth gear 71 of one order, so that when the numeral wheel passes from 9 to 0 or 0 to 9, extension 75 is engaged by the tooth of gear 71 and lever 72 is rocked in a clockwise direction as viewed in Figure 2, the limit of such movement being determined by the engagement of face 75A of extension 75 with the next adjacent tripping lever 72. Lever 72 is also provided with arm 76 extending into the next higher order of the machine and normally engaging lever 72 of such order adjacent to its pivot 73. Arm 76 has bent end 77 (Fig. 1) which extends downwardly and engages rearwardly of annular flange 78 of gear hub 79. Hub 79 carries transfer gear 81 and is slidably mounted on shaft 52 so that rocking movement of tripping lever 72 results in shifting hub 79 and gear 81 forwardly of the machine to position gear 81 in operative relation with respect to the transfer actuator therefor. Single tooth actuator 82 (Figs. 1 and 4) for gear 81 is mounted with actuator 82A of the adjacent lower order by studs 83 on locking disks 63, 63A, the actuators 82 and 82A being spaced apart by integral flanges of studs 83 indicated in dotted lines at 80 in Fig. 4. Actuators 82, 82A and locking discs 63, 63A are assembled as a unit and thereafter placed on shaft 56 and pinned in position thereon. To enable movement of shaft 52 by operation of actuator 82 and to prevent over-throw thereafter, each locking disk 63 is provided with a transfer notch 84 (Fig. 6) spaced from recessed portion 64 by an interposed solid portion 85 of disk 63.

From the above description it is seen that each time a transfer is determined in one order of the machine, gear 81 of the next higher order is moved into active position to be subsequently operated by the associated transfer actuator 82. Means are provided for resiliently maintaining gear 81 in either shifted position thereof and associated with such maintaining means is a restoring cam, which operates with each pair of adjacent gears 81. Gear hub 79 (Fig. 1) has

second annular flange 86 which extends between spaced annular flanges 87 of shaft 88, which is slidably mounted in transverse member 89 secured on frame member 14 and spaced therefrom, and transverse member 91 spaced from member 89 and suitably supported on the frame of the machine. Shaft 88 (Fig. 1) is provided with spaced annular grooves 92 for cooperation with spring urged ball 93 mounted in member 91. Thus, shaft 88 and transfer gear 81 are maintained resiliently in either shifted position thereof. It will be noted that when gear 81 is moved to operative position the forward end of shaft 88 will project beyond member 89 and into the path of restoring cam 96 (Figs. 1 and 4) preferably formed integrally with actuator 82A of each pair of associated transfer actuators 82, 82A. As seen in Figure 4, each pair of shafts 88 for adjacent orders of the machine are spaced closer together than the spacing between the pairs so that both shafts of each pair lie in the path of a single restoring cam 96. Cams 96 operate successively after a transfer to restore any enabled order of the transfer mechanism to disabled condition.

It will be noted in Figure 4 that while two transfer actuators 82, 82A are shown on shaft 56 at the right of the view only one of such transfer actuators is necessary as no transfer occurs in the units order. However, the same transfer actuator construction is provided in such order as in the higher orders because restoring cam 96 must be provided for the second highest order of the machine. It will also be seen that the successive pairs of actuators 82, 82A on the remaining actuating shafts 51 are spaced apart an angular distance to provide for successive operation of the transfer actuators from the lowest to the highest order.

Referring to Figure 5, the respective actuators 82 and 82A for an associated pair of orders in the machine, are shown in the position just before the transfer is effected in the lowest of the orders, and as clearly seen in such view, the transfer actuator 82, which is in leading position in the direction of rotation thereof, is effective after transfer actuator 82A for the lower of the two orders. This arrangement of the transfer actuators is important in enabling the grouping of various pairs of the orders of the selecting mechanism with respect to a single actuating shaft and to enable the completion of a full transfer across the machine.

Briefly, assuming that a transfer has been determined by shifting both of gears 81, (Fig. 5) to active position, transfer actuators 82 and 82A will have rotated from their full cycle position shown in Fig. 4 to the position shown in Fig. 5 where actuator 82A is positioned to move its associated gear 81 for 1/10 rotation to introduce the transferred increment into the associated numeral wheel. Subsequently actuator 82 will become effective with respect to its associated gear 81 to cause a 1/10 rotation thereof and complete the transfer in the associated numeral wheel. Actuator 82 in effect trails behind actuator 82A for a sufficient angular distance to accommodate the setting of the transfer mechanism in the higher order by movement of gear 81 to active position if the transferred increment placed in the lower order numeral wheel associated with gear 81 determines a transfer into the next higher numeral wheel.

In Figure 8, the respective digitation and transfer actuators and the associated orders of se-

lecting mechanism are illustrated schematically, the lowest order of the machine being shown at the left of the figure. In each pair of associated selecting and actuating mechanisms the lower order is shaded with vertical lines and the higher order is shaded with horizontal lines, the digitation actuators being represented by segments of a circle and the transfer actuators being indicated by the small circles spaced about the digitation actuators. The staggered relation of teeth 48, 49 of cylinders 51 extends for approximately 230° of the cycle while the transfer actuators 82 extend for approximately 190° of the cycle and it will be noted that while a digitation is in process in one of the higher orders of the machine, a transfer can occur in a lower order if such has been determined. The actuating shaft 56 at the right of Figure 8 is shown without digitation actuators and only has transfer actuators to provide for a transfer through two higher orders of the machine than those having selecting mechanism associated therewith. If desired, the number of orders having selecting mechanism can be varied to meet individual requirements, in the embodiment shown ten orders are provided with selecting mechanism and two additional orders provided with transfer actuators. The arrangement of the transfer mechanism referred to above provides for a complete transfer through the number of orders noted in a single rotation of the transfer actuators. At the same time, the novel actuating and transfer mechanisms disclosed herein provide a compact machine of convenient size.

While I have described my invention in a preferred embodiment thereof, it is to be understood that such invention may be embodied in other forms and, therefore, I desire that my invention be limited only by the scope of the appended claims.

I, therefore, claim as my invention:

1. In a calculating machine, a single register

- comprising a plurality of ordinally arranged numeral wheels, said numeral wheels being substantially aligned and spaced apart an equal distance from each other and forming a series extending transversely of the machine, a plurality of differential toothed actuators for said numeral wheels arranged in pairs with the actuators of each pair having the same axis of rotation and the teeth of one actuator of each pair being angularly displaced with relation to the teeth of the other actuator of the pair, the axes of said actuators being spaced apart an equal distance from each other and the spacing of said actuator axes being twice the spacing of said numeral wheels, in combination with ordinally arranged differentially operable toothed elements for transmitting selected increments of movement from the actuators of said pairs respectively to adjacent order numeral wheels.
2. In a calculating machine having a single register extending transversely of the machine, said register comprising a plurality of ordinally arranged numeral wheels disposed substantially in line with each other for registering an individual calculated item, a plurality of ordinally arranged differentially operable toothed elements, each said element being adapted to operate one of said numeral wheels, and a plurality of differential actuators in pairs, the actuators of each pair being mounted for rotation about a common axis extending longitudinally of the machine and being cooperable respectively with the differentially operable elements of adjacent order numeral wheels to enter different ordinal values of the individual item in said single register, said differentially operable elements being spaced from each other transversely of the machine, and said differential actuators having operating teeth, the teeth on one actuator being angularly displaced with relation to the teeth of the other actuator on said common axis.

CARL M. F. FRIDEN.
